WILLIAM F. HELMOND, OF HARTFORD, CONNECTICUT, ASSIGNOR TO UNDERWOOD
TYPEWRITER COMPANY, OF NEW YORK, N. Y., A CORPORATION OF DELAWARE.

TYPEWRITING MACHINE.

Application filed March 8, 1922. Serial No. 541,908.

To all whom it may concern:

Be it known that I, WILLIAM F. HELMOND, a citizen of the United States, residing in Hartford, in the county of Hartford and State of Connecticut, have invented certain new and useful Improvements in Typewriting Machines, of which the following is a specification.

In an Underwood typewriting machine, 10 the type-bar strikes a fixed abutment just as it reaches printing position, the point of contact with the abutment being between the ends of the type-bar. The type-bar springs against the platen with sufficient force to 15 make the desired impression, but cannot strike a second time, or make a double impression. This construction usually conduces to clearness and sharpness of the impression, and renders it permissible for the 20 type-bars to be made of considerable length and very thin and light.

In assembling the parts, it has been necessary to secure exactness of relationship between type-bars, the abutment or stop and 25 the platen, it being usually necessary for the type to be within less than five-thousandths of an inch from the platen when arrested by the abutment, and it being also necessary to leave a space of some 30 thousandths of an inch between the type and the platen, so as to avoid blurring or double printing. The permissible variation in the position of the type when arrested by the abutment has therefore been microscopic, and difficult to secure. If the type-bar strikes the abutment a trifle too soon, it 35 results that the type-bar springs excessively in reaching the platen, and the extreme tip of the type therefore makes too heavy an impression, compared with the main portion of the type. This ill effect is produced when the type-bar is not more than ten or fifteen thousandths of an inch away from the platen at the time it strikes 40 the abutment. The abutment is rather near the type end of the bar, causing the bar to spring or bend on a short radius, with the result that the top of the type prints so heavily. The effect is the same as if the type were "off 45 its feet," and the trouble has to be corrected by bending the type-bar with tools, or by fitting the type-bar more closely with relation to the abutment. This is a slow and 50 expensive operation, every type-bar having

to be carefully tested for exactness of relation with abutment and platen.

The lateral vibration of the type-bar is considerable, tending to impair the side alignment and the spacing of the type impressions. The capital letters particularly tend 60 to incline to the right or left when the machine is rapidly operated, the axis of the lateral vibration being at about the point where the type-bar strikes the abutment, which, as already noted, is rather near 65 the type, so that the angular extent of the lateral vibration is considerable.

In overcoming these difficulties, each type-bar is provided with a tongue or device projecting therefrom which strikes the 70 abutment or stop just as the type almost reaches the platen. Said tongue is preferably resilient, and integral with the type-bar. In using this improved bar, the types can be from five thousandths to fifteen thousandths of an inch from the platen 75 when the yielding tongue or buffer contacts with the abutment. The improvement renders close work unnecessary, there being such a large margin that a high degree of 80 skill is not required for adjustment, and the machine can be manufactured more cheaply and rapidly.

After the abutment is struck, the improved bar can yield for a distance that is about equivalent to the entire length of the bar. Owing to this great springing or bending length, the type prints evenly. The difficulty of the top of the type printing the heaviest is overcome. The improved 90 bar can be as far as fifteen thousandths of an inch away from the platen, when it is arrested by the abutment, without printing heavily at the top of the type. This affords considerable advantage in lowering the cost 95 and expediting the work of alignment, since a lower grade of aligning skill can be engaged, microscopic closeness of relationship of the parts not being required, and it being therefore unnecessary to give the usual 100 close attention to testing the type-bars with relation to abutment and platen, a substantial range of variation being permissible.

A further advantage of the improved type-bar is that noise is reduced because 105 the part that strikes the fixed abutment is yielding.

The yielding tongue is springy and pulls

back the type instantly from the platen, eliminating liability to blur. Moreover, since the type-bar starts back more promptly from printing position to its normal 5 position, high speed of operation is favored.

Better carbon-copies are produced, because the type-bar is not stopped so sharply by the abutment, and does not have to bend or spring so much locally as heretofore. The 10 invention has the effect of stopping the type-bar just the way it should be stopped.

In the new type-bar, the lateral vibration does not center at the point of contact with the abutment, as heretofore, but centers at 15 a point close to the pivot of the type-bar, this being due to the use of the spring tongue. The tremor takes place near the root of said tongue, and the lateral vibration of the types is reduced, because the 20 type-bar is very closely supported on both sides by the segment at about the axis of the lateral vibration. The type impressions therefore have better side alignment, and the impressions of the capital types also 25 stand straighter, especially in rapid operation. The type impressions do not flare out to the right or left, and they stand in better vertical alignment. There is a sharper blow of the type on the paper.

30 Said spring tongues may lie exactly in the planes of their type-bars, or be edge to edge therewith, or they may be bent to either side or the other, so as to be out of the planes of their type-bars. In practice, the type ends

35 of the bars are bent at different angles to the body-portions thereof, the bends or elbows being greatest at the sides of the type-bar system. Consequently, when an extreme side type-bar is at the printing point, the 40 weight of the bar is at one side of a straight line joining the type-bar stop to the printing face of the type, where it touches the platen. Inasmuch as the type end of the bar moves at high speed against the platen, 45 it results that the momentum of that portion or elbow of the type-bar which is bent laterally from said straight line tends to spring said elbow, with the result of double printing or blurring of the type impression

50 on the work-sheet. To overcome this defect, said spring-tongue stop is bent laterally from the side of the type-bar opposite to that from which the type-block extends. At the left-hand side of the system, the type-blocks are bent leftward from the type-bars, 55 and the novel stop tongues are illustrated as bent out from the right-hand side of the type-bars. At the right-hand side of the system, the reverse is the case. From this 60 it results that, as each type-bar approaches the platen, it is arrested by the spring tongue at a point somewhat to one side of the body of the bar; or at least the tongue itself is arrested while the body of the bar 65 tends to continue towards the platen. The

type impression therefore is produced by the springing of the type-bar beyond the point where the spring tongue is arrested. When the type is arrested by the platen, the momentum of the elbow-portion of the type-bar causes it to tend to advance still farther; but inasmuch as the type-bar is now supported at the type and at the pivot, it follows that such prolonged motion of the elbow-portion of the type-bar could only have the effect of twisting the bar; but this tendency to twist is intercepted by the spring tongue, which at this moment is under high tension, and which, by reason of its offset position, affords a support to 70 the entire type-bar against twisting in this very direction. The result is that the entire momentum of the type-bar is utilized to make a strong, clear impression of the type on the work-sheet, and twisting of the bar 75 minimized or eliminated. Viewed in another way, the type-bar, as soon as its spring tongue is arrested, tends to twist laterally away from said spring tongue; and thereafter when the type strikes, (and when, therefore, the spring tongue is under 80 high tension) a tendency is set up for the type-bar to twist in the opposite direction from the first; and these two twisting tendencies counteract each other, while the 85 spring tongue also opposes the final twisting tendency of the bar.

Other features and advantages will hereinafter appear.

In the accompanying drawings,

Figure 1 is a plan of the type-bar portion of an Underwood front-strike type-writing machine; the spring tongues at the left-hand side of the system being bent to the right; and those at the right-hand side 105 of the system being bent to the left, to varying degrees, depending upon the degree of bending of the type ends of the bars.

Figure 2 is a sectional side elevation, showing the type-bar in printing position.

Figure 3 is a front elevation of the type-bar segment and platen, showing the graduated leftward bends of the spring-tongue stops of the type-bars at the right-hand side 115 of the system.

The type-bars 1 are pivoted on a fulcrum-wire 2, and are operated by key-driven levers 3. The wire 2 is mounted in a segment 4, which has radial guide-slots 5 for the type-bars; said segment being provided with a dust-shelf 6 over the slots. The type strikes rearwardly against a platen 7. Each type-bar is a plate of thin sheet-metal having a longitudinal stiffening rib (not shown).

Extending upwardly from the base portion of the type-bar, towards the free end thereof, is a tongue 10, to contact with an abutment 11 on the front face of the segment 4, this abutment being of arc shape,

suitable for all the type-bars. The spring tongue may be formed by cutting a long kerf or slot 12 at the middle of the bar, at a widened portion thereof, said widened portion beginning at 13 just above the dust-shelf 6. The tongue 10 may be of any required length, the arc of the abutment being made of smaller radius where the tongue is longer.

10 When the tongue strikes the abutment, there is springing action, beginning at the abutment and extending down through the tongue and then up along the type-bar to the type 9; the tongue and type-bar both having 15 a springy construction. This gives a length of spring which is about equivalent to the entire length of the type-bar, and the type can spring very much more than heretofore after the type-bar strikes the abutment, 20 and there is more uniformity of type impression, and less need of securing the precise relation heretofore found necessary between the type, the platen and the abutment.

The abutment 11 is barely raised from 25 the front surface of the segment. This permits the axis of the middle body-portion of the type-bar to be more nearly coincident with a line drawn from the pivot to the type, thus tending to reduce liability 30 of skewing and distortion of the type-bar at the moment of printing. The slotted portion of the segment projects far forwardly from the face of the segment, and the standing type-bar at its bottom portion 35 bends in close to the front face of the segment, and keeps this close relationship for the rest of the distance to the type.

It will be understood, from Figure 3, that 40 the type-bars, when printing, occupy various positions radiating from the printing point, according to the positions of the bars in the segment 4. However, the types 9 must occupy vertical positions, and hence elbows are 45 bent in the type-bars near their type ends, at 18, just below the usual fixed central type-guide 14. Taking the case of the extreme right-hand type-bar, at Figure 3, it will be seen that the elbow-portion of the bar from the type down to the bend 18, 50 and from said bend to the abutment 11, stands considerably to one side of an imaginary line drawn from the type to the point where the type-bar crosses the abutment 11, and all this portion of the bar has heretofore 55 tended to continue in motion after the type is arrested by the platen, thereby setting up a tendency of the type-bar to twist, with a consequent blurring of the type impression. To reduce or overcome this difficulty, the spring tongue 10 is bent to the left 60 from the type-bars on the right-hand side of the system, at Figure 3, with the result that the tendency of the elbow-portion of the bar to continue in motion or to twist, in 65 the manner stated, is met by the resistance

offered by the engagement of the offset spring tongue with the stop-abutment 11. In other words, the tendency of the elbow-portion of the bar is to twist to the left, and this is overcome by the support which is 70 offered at the left of the type-bar by the bent-out spring tongue, at Figure 3, the point of bending of the tongue being indicated at 15. One of the distinctions over

previous type-bars is therefore that the point of arrest and support at 19 is set considerably over from the elbow-portion of the type-bar in a direction to overcome its tendency to twist at the instant of printing. As the type approaches the platen, the offset 75 spring tongue 10 is first arrested by reason of its engagement with the abutment 11. The type and the main portion of the type-bar are not arrested, however, but continue on because of their momentum, and since 80 this final motion cannot take place about the pivot 2, it takes the nature of a bowing or whipping of the bar, with a tendency to twist towards the right, at Figure 3, or away 85 from the point 19 where the spring tongue strikes the abutment 11. The momentum of the types 9 is taken up by the platen 7. The momentum of the elbow-portion of the type-bar, including the bend 18, tends to 90 continue its advance towards the platen. Since at this time the bar is supported not only at its pivot but also at its type, this final springing of the type-bar can only be 95 in the nature of a longitudinal twist of the bar towards the left; but this twist is powerfully opposed by the offset spring tongue 10, which is also at the left of the main portion of the bar, and which at this time is under high tension and therefore effective 100 to counteract the twisting tendency of the bar. Thus, by offsetting the tongue 10, there is first set up a tendency of the bar to twist 105 to the right, which counteracts to a great extent the subsequent tendency of the bar to twist to the left; and the last-named tendency is also strongly opposed by the offset 110 spring tongue itself. At Figure 1, it will be seen that the tongues for the type-bars at the left-hand portion of the system are 115 bent to the right, inasmuch as their type ends are bent to the left.

Variations may be resorted to within the scope of the invention, and portions of the improvements may be used without others.

Having thus described my invention, I claim:

1. The combination with a platen, of a pivoted type-bar to print against said platen and having an elbow or bend near its type end whereby the type stands at one side of the body of the bar, a type-bar stop-device, and a single tongue on the type-bar to engage said stop-device before the type touches the platen, said tongue extending from the type-bar near its pivot portion towards its 125 130

type end and being bent to the side of the type-bar opposite the type to counteract the twisting tendency due to the form of the type end of the type-bar.

- 5 2. The combination with a platen, of a type-bar to print against said platen and having an elbow or bend near its type end whereby the type stands at one side of the body of the bar, and means for checking 10 the typing movement of said type-bar and counteracting the twisting tendency due to said elbow, comprising a tongue formed by a longitudinal kerf in said type-bar and bent to the side opposite the type and a type-bar stop to be engaged by said tongue just before the type-bar engages the platen.
3. The combination with a platen, of a plurality of radially-arranged pivoted type-bars, each having an elbow or bend near 20 its type end whereby the type stands at one side of the body of the bar, means to guide the type-bars laterally at their pivots, a type-bar guide to be engaged by the free ends of all the type-bars, a type-bar stop-device about midway between the pivots of the type-bars and the type-bar guide, and a single resilient stop-device-engaging tongue on each type-bar having an elbow, the tongues joining the type-bars in proximity 30 to said lateral guiding means and extending to the sides of the type-bar opposite the types to counteract the twisting tendency due to the elbows at the type ends of the type-bars.
- 35 4. A pivoted type-bar formed of thin metal and having near its type end an elbow or bend whereby the type stands at one side of the body of the bar, and near its pivot portion a single integral tongue extending 40 towards its free end, and a stop to be engaged by the free end of the tongue just before the type strikes the platen, the type-bar and the tongue being both resilient, to permit the type to spring to the platen after 45 such arrest, and the tongue being bent in a direction opposite to the direction of the bend at the type end of the type-bar to counteract the twisting tendency due to the bend at the type end.
- 50 5. The combination with a platen, of a type-bar to swing against the platen, said type-bar having an elbow or bend near its type end whereby the type stands at one side of the body of the bar, and arresting 55 means to engage the bar between its ends and at one side only of the body of the

type-bar, when the type reaches the proximity of the platen, to control the twisting tendency of the type-bar, so as to cause the type on the bent end of the type-bar to 60 strike the platen properly.

6. The combination with a platen, of a type-bar to swing against the platen, said type-bar having an elbow or bend near its type end whereby the type stands at one 65 side of the body of the bar, and arresting means to engage the bar between its ends and only at the side of the body of the type-bar opposite the type, when the type reaches the proximity of the platen. 70

7. The combination with a platen, of a type-bar to swing against the platen, said type-bar having an elbow or bend near its type end whereby the type stands at one side of the body of the bar, and arresting 75 means to engage the bar between its ends, when the type reaches the proximity of the platen, the portion of the type-bar for engagement with the arresting means being bent to the opposite side of the type-bar 80 from the type.

8. The combination with a platen, of a type-bar to swing against the platen, said type-bar having an elbow or bend near its type end whereby the type stands at one 85 side of the body of the bar, and arresting means to engage the bar between its ends, when the type reaches the proximity of the platen, a portion of the type-bar being bent to the opposite side of the type-bar from 90 the type, to engage said arresting means, said offset portion being in the form of a tongue extending laterally from and longitudinally of the type-bar.

9. The combination with a platen, of a 95 type-bar to swing against the platen, said type-bar having an elbow or bend near its type end whereby the type stands at one side of the body of the bar, and arresting means to engage the bar between its ends 100 when the type reaches the proximity of the platen, said type-bar having a single offset portion to engage said arresting means, said offset portion being bent to the opposite side of the type-bar from the type, and being in 105 the form of a tongue extending laterally from the type-bar, both the type-bar and the tongue being resilient.
